(57) **CLAIM**

I claim the ornamental design for a bottle, as shown and described.

DESCRIPTION

FIG. 1 is an upper perspective view of the bottle showing my design;

FIG. 2 is a front elevation view thereof, a back elevation view, a side view and an opposite side view being identical to the front view thereof;

FIG. 3 is a top view thereof; and,

FIG. 4 is a bottom view thereof.

1 Claim, 2 Drawing Sheets

FIG. 1

FIG. 2

FIG. 3

FIG. 4
